CRUCIBLE SKIMMER

Virgil H. Todd, Rockford, Ill.

Application August 11, 1945, Serial No. 610,297

7 Claims. (Cl. 22—83)

1

This invention relates to the skimming of crucibles for pouring molten metal such as brass or bronze.

The primary object is to provide a skimmer adapted to be movably mounted on a crucible and actuated automatically as an incident to tilting thereof so as to be maintained in proper skimming position in all degrees of tilt of the crucible.

A more detailed object is to provide a skimmer of the above character which is actuated by the buoyant force exerted thereon by the molten metal being poured.

Another object is to support such an automatically actuated skimmer on a member which may be utilized as a cover for the crucible to be skimmed.

Other objects and advantages of the invention will become apparent from the following detailed description taken in connection with the accompanying drawing, in which

Figure 1 is a perspective view of the improved skimmer.

Figs. 2 and 3 are diametrical sectional views of the skimmer attached to a crucible shown in different positions.

While the invention is susceptible of various modifications and alternative constructions, I have shown in the drawing and will herein describe in detail the preferred embodiment. It is to be understood, however, that I do not intend to limit the invention by such disclosure, but aim to cover all modifications and alternative constructions falling within the spirit and scope of the invention as expressed in the appended claims.

The invention is illustrated in the drawing as applied to the ordinary crucible 5 composed of so-called crucible material which is a mixture of graphite and clay bound together into a compact mass. Crucibles of this character have a pour lip 6 at their open ends and are commonly used in handling molten metal, particularly brass and bronze. In pouring such metal into a mold 8, the slag 9 which collects on the surface must be skimmed off, this usually being done by a separate skimmer manually held in position adjacent the spout 6. To permit this, the crucible is ordinarily left uncovered, with the result that the zinc fumes fill the adjacent air and become oxidized.

The present invention contemplates relieving this unhealthful condition in brass foundries and the like and in saving labor through the provision on the crucible of a skimmer 10 arranged in a novel manner so as to be actuated automatically and always maintained in proper skimming position in all degrees of tilting of the crucible. In the form shown, the skimmer comprises the surface 11 of a block 12 movably mounted on the crucible in a position to project into the body of molten metal adjacent the spout

2

6 and block the outflow of the slag 9 during pouring of the metal from the crucible.

In accordance with another aspect of the invention, the skimmer 10 is mounted on a member which forms a cover for the crucible. Herein this cover comprises a flat metal disk 16 adapted to fit against and cover the open end of the crucible except for a peripheral opening 13 of rectangular shape positioned opposite the spout 10 so as to permit metal to be poured from the covered crucible while the cover remains attached. Such attachment is effected in the present instance by arms 14 fastened at spaced points around the periphery of the cover and depending from the latter in positions to fit over the crucible end and frictionally grip the external surface thereof. The cover plate may be lifted off from the crucible by a handle 15 secured to the upper surface of the cover.

20 The skimmer 10 projects downwardly through the pouring opening 13 adjacent the inner or closed end thereof and its movement to different skimming positions is provided for by suspending the upper end of the block 12 from a pivot 17 extending parallel to the plate 16 and spaced a short distance above the latter. As shown, the pin extends through a bore in the block 12, and its opposite ends are supported in lugs 18 upstanding from the top of the cover on opposite sides 25 of the opening 13. Thus, when the crucible is in normal upright position, the skimmer block 12 hangs downwardly and lies adjacent the straight inner edge 19 of the cover opening with the lower free end of the block projecting into the crucible 30 several inches below the under side of the cover. The block is thus disposed adjacent the inner surface of the crucible (Fig. 2) adjacent the pouring spout 6.

Automatic actuation of the skimmer surface 40 11 to maintain the same in proper skimming position is effected by a buoyant force derived by engagement of the molten metal in the crucible with the movable skimmer. To this end, the block 12 which carries the surface 11 is constructed of an inert material which will withstand the temperatures encountered by dipping into the molten metal and at the same time will float on the molten metal. The same material 45 of which the crucible walls are made is suitable for this purpose, the block 12 being approximately one inch thick in this instance.

As the crucible equipped with the improved skimmer and cover is tilted from the upright 55 position (Fig. 2), the lower free end of the block 12 remains against the inner surface of the crucible until the molten metal level reaches it, the pivot 17 then being offset outwardly from the block end. When the molten metal 60 encounters the block, the latter dips through the

slag layer and into the metal, remaining against the crucible wall until the buoyant force exerted vertically on the free end of the block overcomes the eccentric weight of this block end. Thereupon, the block end is buoyed upwardly away from the crucible wall as shown in Fig. 3, permitting metal to flow out beneath the block. The surface 11 of the latter is thus positioned to block the outflow of the slag 9 thus skimming the metal poured from the crucible. As the crucible is tilted further, the skimmer adapts itself automatically to the liquid level and thus moves relative to the crucible so as to remain in the same skimming relation with respect to the liquid level.

By utilizing the buoyancy of the skimmer in this way, the metal poured from the crucible is skimmed automatically and effectually and by a very simple construction. A substantial saving in labor is thus achieved and at the same time the crucible is covered so as to minimize the dangers resulting from the escape of the metal vapors.

By maintaining the crucible covered, oxidation of the metal within the latter and the formation of slag on the internal side wall is kept at a minimum.

I claim as my invention:

1. The combination of a plate for covering the open end of a crucible for containing molten metal, means on said plate adapted to interfit with the lip of the crucible and hold the plate in place when the crucible is tilted, said plate having a radially opening peripheral notch therein, a skimmer member projecting downwardly through said notch and spaced inwardly from the periphery of said plate, and means suspending said member from a pivot disposed above said plate for inward swinging under the buoyancy of the molten metal on which the free end of the member floats when the crucible is tilted to pouring position.

2. The combination of a plate for covering the open end of a crucible for containing molten metal, means on said plate adapted to interfit with the lip of the crucible and hold the plate in place when the crucible is tilted, said plate having a peripheral opening through which metal may be poured from said crucible when the latter is tilted, and a skimmer member pivotally suspended in said opening and actuated to skimming position automatically by engagement with the molten metal flowing through said opening as the crucible is tilted.

3. The combination of a cover adapted to fit the end of a crucible and having a rectangular peripheral opening through which molten metal may be poured from the crucible, a generally rectangular member projecting through said opening and composed of a material which is lighter than molten metal such as brass, and means suspending said member from a pivot disposed above and parallel to the cover and parallel to one edge of said opening whereby to cause inward swinging of the free lower end of the member under the buoyant force exerted thereon by the molten metal being poured from said crucible when the latter is tilted.

4. The combination of a cover for a crucible adapted to contain molten metal such as brass, said cover having an opening through which molten metal may flow when the crucible is tilted, a member disposed in said opening and composed of a material lighter than said metal, and means

70
75

on said cover supporting said member for movement of its lower end inwardly away from the crucible wall under the buoyant force of the molten metal and the maintenance of the member in skimming position in all positions of tilting of the crucible.

5. For use on a pouring crucible for containing molten brass or the like, the combination of a cover for the crucible having a peripheral opening, a member projecting through said opening to provide a skimming blade on one side of the cover, said blade being composed of material adapted to float on molten metal, and means pivotally supporting one end of said member on the other side of the cover for swinging of the member about an axis spaced from and extending parallel to the cover.

6. The combination of a plate for covering the open end of a crucible for containing molten metal, means on said plate adapted to interfit with the lip of the crucible and hold the plate in place when the crucible is tilted, said plate having a radially opening peripheral notch therein, a skimmer member projecting downwardly through said notch and spaced inwardly from the periphery of said plate, and means suspending said member from a pivot disposed above said plate for inward swinging under the buoyancy of the molten metal engaging the free end of the member when the crucible is tilted to pouring position, the root of said notch being positioned to engage said skimmer member and limit inward pivoting thereof after partial tilting of said crucible.

35 7. The combination of a plate for covering the open end of a crucible for containing molten metal, means on said plate adapted to interfit with the lip of the crucible and hold the plate in place when the crucible is tilted, said plate having a radially opening peripheral notch therein, a skimmer member projecting downwardly through said notch and spaced inwardly from the periphery of said plate, means suspending said member from a point parallel to and disposed above said covering plate so that the member lies along a chord of the crucible and is swingable outwardly against the inner wall thereof in the initial tilting of the crucible and then swings inwardly away from such wall under the buoyancy of the molten metal engaging the free end of the member in the further tilting of the crucible, and a stop on said cover plate engageable with said member to limit said inward swinging to a position in which the member is disposed approximately normal to the cover plate.
